UNITED STATES PATENT OFFICE.

JOHN M. KELLEY, OF ROCHESTER, NEW YORK.

PUMP.

1,170,756.

Specification of Letters Patent.

Patented Feb. 8, 1916.

Application filed March 16, 1914. Serial No. 825,080.

To all whom it may concern:

Be it known that I, JOHN M. KELLEY, of Rochester, in the county of Monroe and State of New York, have invented a new and useful Improvement in Pumps, which improvement is fully set forth in the following specification and shown in the accompanying drawings.

The present invention relates to pumps and more particularly to that type used in sprayers or the like for spraying fire extinguishing liquids and employing a container with an attached pump, an object of the invention being to improve the construction of the pump so that none of the liquid can enter the pump chamber, while, at the same time, the valve between the pump chamber and the liquid container is prevented from "freezing" or sticking to its seat.

To these and other ends, the invention consists in certain parts and combinations of parts all of which will be hereinafter described, the novel features being pointed out in the appended claims.

In the drawings: Figure 1 is a vertical section through a sprayer embodying the present improvements; Fig. 2 is an enlarged vertical section through the lower end of the pump; and Fig. 3 is a horizontal section on the line *a—a*, Fig. 2.

In fire extinguishers of the type employing carbon tetrachlorid as the extinguishing liquid, great difficulty has heretofore been experienced in keeping the liquid from the pump chamber when a portion of the latter has been immersed in the liquid, and it has been found that when a cup-shaped leather piston is employed in such a sprayer, the effectiveness of such piston is immediately destroyed upon contact with the carbon tetrachlorid. It has also been found that even though non-corrosive metal be employed in the valve of the pump, such valve will stick or "freeze" to its seat under the action of carbon tetrachlorid.

The above disadvantages are overcome by the construction herein set forth in which—

1 indicates the container of any suitable construction preferably having a manually controllable discharge nozzle 2 and provided with a fire extinguishing or other liquid 3. The top wall of the container may be provided with a central opening formed by a sleeve 4 which is internally threaded to receive an externally threaded cap 5 on the

upper end of the pump cylinder 6 which forms the pump chamber, the cap being provided with openings 7 to permit the intake of air within the pump chamber above the 60 piston to be described.

The lower end of the cylinder 6 may be closed by a head 8 which may be provided with a central discharge opening 9 and the latter may be closed by a valve 10 preferably 65 in the form of a plunger having a cone-shaped upper end 11 for seating against the lower end of the discharge passage 9. The tapered portion of this valve may operate within the chamber 12 formed at the lower 70 end of the discharge passage 9 and having suitable clefts 13 communicating with the interior of the container 1. The lower wall of this chamber 12 may be in the form of a bushing which closes the chamber and 75 guides the plunger 10. A coiled spring 15 may abut the shoulders formed by the tapered upper end of the valve and the upper surface of the bushing and tends normally to cause the valve to close. 80

Within the pump chamber, a pump piston is arranged and preferably embodies a cup-shaped leather member 16 held to a rod or stem 17 between the disks 18 and 19 by a nut 20 which presses said disks in firm engagement with the central portion of the cup piston, the nut and washers operating on a reduced screw threaded portion of the piston rod 21 and the screw threaded portion being projected beyond the nut so that 85 it may be made to extend at 22 into the discharge passage 9 in order to engage with the upper end 11 of the valve 10 so as to displace the valve from its seat. This engagement between the extension 22 on the 90 pump piston and the valve cannot occur during the normal operations of the pump piston but only after the extension has been rotated in order to engage with the screw threaded wall 23 of the discharge opening. 95 Prior to the disengagement of the valve from its seat by the extension 22, the latter has, by its engagement with the screw threaded portion 23, formed an effective valve or closure for the discharge opening 100 105 9, so that, when the valve 11 is displaced from its seat, liquid cannot flow from the container 1 into the pump chamber by way of the discharge 9.

Another feature which adds to the life of 110 the pump is the means for ironing or pressing out the operative flange of the pump pis-

ton. This is accomplished by providing an annular pocket 24 preferably at the lower end of the pump chamber by forming an upward annular extension 25 on the head 8, 5 the upper part of said annular pocket being wider than the lower part in order that the flange of the piston, even though slightly distorted or wrinkled, may enter the pocket, the turning of the piston and the advancement thereof by the screw thread serving to 10 press or iron out the flange until finally the latter is received within the restricted portion of the annular pocket 24.

From the foregoing, it will be seen that 15 there has been provided a sprayer in which the valve between the pump and the container can be held away from its seat when the device is inoperative, while yet effectively closing the communication between 20 the cylinder and the pump chamber to prevent the entrance of the liquid within the pump chamber. Furthermore, the pump is provided with means which permits the pressing or spreading of the cupped pump 25 piston and thus insures that the pump will be ready for action even though the same has not been used for considerable time. The screwing down of the pump piston rod holds the same in a fixed position so that 30 the piston cannot work outward to its possible detriment. For instance, when the sprayer is carried in an automobile, motor boat, or other vehicle, if the handle were not so fixed, the rod could or might become bent 35 or, if carried loosely with other things such as tools, etc., the handle might become caught or entangled, thus delaying the necessary quick application of the fluid to the fire.

What I claim as my invention and desire 40 to secure by Letters Patent is:

1. A pump comprising a cylinder having an outlet, a piston, and a valve controlling said outlet, the piston carrying a projection rigid therewith and movable into engagement with the valve to open the communication.

2. A pump comprising a cylinder having an outlet, a piston and a valve controlling said outlet, the piston carrying a portion

arranged to open the valve and to close the 50 outlet when the piston is moved to open the valve.

3. A pump comprising a cylinder having an outlet, a piston and a valve controlling said outlet, the piston carrying a portion arranged to open the valve and to close the outlet, said portion being in the form of a projection arranged to enter and close said outlet prior to the opening of the valve.

4. A pump comprising a cylinder having 60 an outlet, a piston, and a valve controlling said outlet, the piston carrying a portion arranged to open the valve and to close the outlet, said portion being in the form of a projection arranged to enter and close said outlet prior to the opening of the valve, and the walls of the outlet having interlocking screw threads so that the projection is advanced toward or removed from the valve as said projection is rotated.

5. A pump comprising a cylinder having a head formed with a discharge passage, a spring pressed valve arranged to close said passage, a cup-shaped leather piston operating in said cylinder, a piston rod carrying 75 said piston and projecting beyond the latter to enter the discharge passage to close the latter and then to open the valve.

6. A pump comprising a cylinder having an internal annular pocket at one end, a cup-shaped piston operable in said cylinder, and a screw portion carried by the piston and adapted to cause the flange of the piston to enter the pocket.

7. A pump comprising a cylinder having 85 an internal annular pocket at one end and a screw threaded portion, a cup-shaped piston operable in said cylinder, and a piston rod connected to the piston and having a screw threaded portion adapted to coöperate with 90 the screw threaded portion on the cylinder to cause the flange of the piston to enter the annular chamber to be pressed out by the latter.
